UNITED STATES PATENT OFFICE.

ALFRED S. STALLINGS, OF ATLANTA, GEORGIA.

DISPLAY-CABINET.

1,261,455.

Specification of Letters Patent. Patented Apr. 3, 1918.

Application filed October 28, 1916. Serial No. 129,260.

To all whom it may concern:

Be it known that I, ALFRED S. STALLINGS, a citizen of the United States, residing at Atlanta, in the county of Fulton and State 5 of Georgia, have invented certain new and useful Improvements in Display-Cabinets, of which the following is a specification.

This invention relates to an improved cabinet and has as its primary object to provide 10 a device of this character particularly designed for containing and displaying candies in stores.

The invention has as a further object to provide a cabinet having a plurality of 15 trays in which the candy may be displayed and wherein the cabinet will also be equipped with drawers for containing a stock of the candy so displayed.

The invention has as a still further object 20 to provide an arrangement wherein the drawers will be mounted to normally gravitate to closed position and wherein stop members will be provided for limiting the drawers in their movement to open position and supporting the drawers when so opened.

And the invention has as a still further object to provide a device of this character which will be thoroughly sanitary and which will be of such nature that it may be easily 30 moved from place to place.

Other and incidental objects will appear as the description proceeds and in the drawings wherein I have illustrated the preferred embodiment of the invention and wherein 35 similar reference characters designate corresponding parts throughout the several views:

Figure 1 is a perspective view of my improved cabinet particularly showing the arrangement of the display trays therein,

Fig. 2 is a perspective view showing the rear side of the cabinet and particularly showing the arrangement of the drawers employed,

Fig. 3 is a transverse sectional view particularly showing the mounting of the drawers as well as the general construction of the cabinet,

Fig. 4 is a longitudinal sectional view 50 illustrating the combined stop and retaining members for the drawers, and

Fig. 5 is a detail perspective view showing one of the display trays removed.

In carrying out the invention, my improved cabinet is formed with substantially 55 triangular shaped ends 10. Extending be-

tween the ends is a front sill 11 and a back sill 12. Connecting the ends at the upper rear extremity of the cabinet is an upper cross piece 13 and arranged between the said cross piece and the sill 12 is a middle cross piece 14. Extending between the ends and spaced a slight distance in the rear of the sill 11 is a bottom cross piece 15. The sills and several cross pieces may be secured to 60 the ends in any approved manner.

The ends 10 along their forwardly sloping margins, are rabbeted upon the inner sides thereof to slidably receive a front transparent pane 16 which, at its lower extremity, 70 is received within a suitable groove in the front sill 11, with the said sill supporting the pane in position. The pane 16 is preferably formed of plate glass although any other suitable transparent pane may be employed. The ends 10 are also transversely rabbeted at their upper extremities to slidably receive a top pane 17. The pane 17, as in the instance of the pane 16 is also preferably formed of plate glass and at its forward extremity, is arranged to overlie the upper edge of the pane 16 for locking the latter pane upon the cabinet. Extending 75 forwardly from the middle cross piece 14 and supported by the said cross piece and 80 the ends 10 of the cabinet is a horizontally arranged shelf 18 defining upper and lower compartments within the cabinet. Closing the upper compartment, are sliding doors 19 supported between the cross pieces 13 and 14. 85 These doors 19 may be of any approved type and are preferably provided with roller bearings so that the said doors may move freely 90 with respect to each other. Mounted upon the inner sides of the doors are mirrors 20, 95 this arrangement adding materially to the attractiveness of the cabinet.

Mounted within the forward extremity of the lower compartment of the cabinet, are a plurality of display trays including trays 100 21 of similar construction and a tray 22 arranged between the trays 21 with the said trays fitting snugly side by side between the ends 10 of the cabinet. The trays 21 and 22 are all preferably formed of suitable 105 white enameled-ware and at the open sides thereof are provided with lateral end flanges 23 and side flanges 24. The trays 21 are formed with transverse partitions 25 defining upper and lower compartments in the 110 said trays while the tray 22 has its bottom wall rebent upon itself as more particularly

shown in Fig. 3 to provide a plurality of shelves 26 within the said tray.

Extending within the lower compartment of the cabinet are vertical partitions 27 abutting the shelf 18 and dividing the said lower compartment into a plurality of drawer receiving sections. The trays 21 and 22 are arranged to close these sections at their forward extremities and are supported in inclined position between the shelf 18 and the bottom sill 11 of the cabinet. The trays 21 are arranged within the end sections with the side flanges 24 thereof engaging with the end members 10 and the vertical partitions 27, while the upper end flanges 23 of the said trays are engaged with the forward edge of the shelf 18 with the lower end flanges 23 of the said trays engaging within the groove in the sill 11 for the lower edge of the pane 16. The tray 22 is arranged between the partitions 27 with the side flanges thereof engaging with the said partitions and with the end flanges of the said trays respectively engaging with the forward edge 25 of the shelf 18 and within the groove in the sill 11 as in the instance of the trays 21. The several trays are thus securely mounted in position and attention is now directed to the fact that the inner face of the sill 11 is 30 beveled or cut away to provide an inclined seat 28 for the lower ends of the trays. Owing to the depth of the tray 22, this tray is, at its lower extremity, formed with a shoulder 29 for engagement with the said seat with the adjacent end wall of the tray sloping inwardly to conform to the lines of the cabinet.

Arranged at the bottom of the several sections of the lower compartment of the cabinet is an inclined floor which is formed of sections 30. These floor sections are preferably constructed of metal with the sides thereof flanged and connected by the said flanges to the sides 10 of the cabinet and 45 the partitions 27 with the forward ends of the said sections secured to the cross piece 15 and with the rear ends thereof secured to the sill 12. Slidably mounted upon these floor sections and arranged within the several sections of the lower compartment of the cabinet, are a plurality of drawers 31 provided with flanged heads 32 for engagement with the cross pieces 14 and the sill 12 with the inner extremities of the drawers cut 50 away to conform to the inclined inner faces of the trays 21 and 22. As will now be best observed upon reference to Fig. 3, the sill 12, at its inner upper corner, is cut away to receive a plurality of rollers 33 for engagement with the bottoms of the drawers and 55 mounted upon the sides of the drawers at their forward extremities, are laterally projecting rollers 34 engaging with the floor sections 30 to coöperate with the rollers 33 for freely supporting the drawers. Conse-

quently, it will be seen that owing to the inclination of the floor sections 30, the drawers will normally gravitate to closed position. In this connection, it is to be noted that the cross piece 15 is arranged to engage the inner ends of the drawers when closed and this cross piece provides a stop for the said drawers so that when the drawers are shifted inwardly, the said stop will engage the drawers to limit the said drawers in their inward movement and relieve any shock upon the drawer heads 32. The drawers 31 are, of course, provided with suitable handles 35.

Connected to the inner sides of the ends 10 of the cabinet and to the vertical partitions 27 are a plurality of combined stop and retaining members 36 for the drawers. These retaining members are in the nature of angle irons each supported by one of its flanges with the other flange thereof extending laterally to engage over one of the rollers 34 upon the drawers 31. The members 36 are arranged to extend substantially parallel to the floor sections 30 and at their outer 90 extremities, are bent downwardly toward the said floor sections to provide stops 37. Accordingly, it will be seen that when the drawers 31 are shifted within the cabinet, the retaining members 36 will engage over 95 the rollers 34 to prevent the drawers from tilting upon the rollers 33 while, when the drawers are drawn outwardly, the rollers 34 will engage with the stops 37 of the said members, as shown in dotted lines in Fig. 3, 100 to limit the drawers in their outward movement.

The cabinet, as thus described, may, of course, be constructed any desired size but is preferably of such nature that it may be 105 kept upon the ordinary store counter for displaying candies and the like. By withdrawing the top pane 17 and lifting the front pane 16 upwardly, candy may be placed within the compartments of the trays 110 21 and upon the shelves 26 of the tray 22 to be displayed within the said trays. The shelf 18 is, as will be clear, also adapted to receive an assortment of candy for display and access to the candy within the upper 115 compartment of the cabinet is, of course, had by means of the doors 19. The drawers 31 are designed to receive a stock of the candy displayed so that when a customer indicates a particular kind of candy desired, the 120 drawers may be opened and the candy furnished from the stock thereof without the necessity of molesting the candy upon display. Since the drawers are normally arranged to gravitate to closed position, the 125 stock of candy will be kept in a fresh condition. Moreover, it is to be observed that the front pane 16 is arranged to tightly close the trays 21 and 22 so that the candy within the said trays will also be kept in a fresh 130

condition. The upper compartment of the cabinet is, as will be observed, tightly closed by the doors 19.

It will therefore be seen that I provide a particularly efficient construction for the purpose set forth. By displacing the front pane 16 as previously described, the trays 21 and 22 may be easily removed to be cleaned while, by shifting the drawers 31 inwardly and tilting the inner ends of the said drawers upwardly so that the rollers 34 will ride over the guide members 36, the said drawers may be easily displaced. Consequently, the entire structure may be maintained in a thoroughly sanitary condition.

Having thus described the invention, what is claimed as new is:

1. A display cabinet including a cabinet body having a front sill provided with a

groove, a front pane for the cabinet body seated in said groove, a display tray provided with flanges at its ends, the flange at the lower end of said tray engaging in said groove, and shelf forming means within the cabinet body engaged by the flange at the upper end of the tray for supporting the tray in position beneath the said pane.

2. A display cabinet including a cabinet body having a front sill, a front pane for the cabinet body seating against said sill, a display tray having flanges at its ends, the flange at the lower end of said tray engaging said sill, and shelf forming means within the cabinet body and engaged by the flange at the upper end of the tray for supporting the tray in position beneath the said pane.

In testimony whereof I affix my signature.

ALFRED S. STAULINGS. [L.S.]
